UNITED STATES PATENT OFFICE.

ALBEN E. LUNDELL, OF NEW YORK, N. Y., ASSIGNOR TO WESTERN ELECTRIC COMPANY
INCORPORATED, OF NEW YORK, N. Y., A CORPORATION OF NEW YORK.

TELEPHONE-EXCHANGE SYSTEM.

1,252,911.

Specification of Letters Patent.

Patented Jan. 8, 1918.

Application filed October 28, 1916. Serial No. 126,311.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to registering and 10 controlling equipments for telephone exchange systems, and more particularly to an equipment of this character in which quick-acting relays are employed to perform the functions previously performed by various 15 types of automatic switches.

This application is in part a continuation 20 of the applicant's previously filed applications, Serial No. 56,653 filed October 19, 1915, Serial No. 57,711 filed October 25, 25 1915 and Serial No. 65,986 filed December 9, 1915, the subject matter disclosed in such previously filed applications being also disclosed in this application. Registering and controlling devices are well-known in the 30 art, and are used in connection with automatic telephone switches for the purpose of registering or storing the desired number and subsequently for controlling the setting of automatic switches in accordance with 35 the number thus stored by the register. It has also been proposed heretofore to employ a registering and controlling equipment which is adapted to be set or to register the designation of the particular line which it 40 is desired to select in accordance with one system of notation, and to provide controlling impulses arranged in accordance with another system of notation, such operation being known as translation.

45 In accordance with a feature of the invention, a registering and controlling device is provided in which the designation of the desired line is registered by means of relays, which relays are adapted to be operated in various combinations in registering the number of the desired line, and to control, when so operated, the production of controlling impulses which may be different in number and in arrangement from the number registered.

50 More specifically, in accordance with this feature of the invention, the designation of the desired line is recorded by the depression of certain keys which are decimallly ar-

ranged, the depression of such keys serving 55 to energize register relays in various combinations for registering the number recorded on the keys. As it is desired to control selection in automatic switches in which the terminals are not arranged decimallly, means are provided, operating in connection with the register relays, to translate the number registered into controlling impulses which do not bear a decimal relation 60 to each other. As will more clearly appear 65 from the detailed specification, the non-decimal arrangement of the terminals in the selector switches may necessitate a number of selective acts in the switches which is greater than the number of digits representing 70 the desired line, and in accordance with a feature of the present invention the extra set of controlling impulses necessary to bring about the selection of the desired line is automatically provided by means of the registering relays in response to the operation 75 of a single key for each digit of the desired number.

In the system disclosed herein with which the registering and controlling device is 80 adapted to operate, the connector switches are each provided with terminals individual to five hundred lines, which terminals are divided into five groups of one hundred, which groups are subdivided into ten groups 85 of ten units. Four of such switches thus provide the terminals for two thousand lines. The intermediate or group selectors which are used with such connector switches, are arranged to select an idle trunk in a group 90 of trunks leading to connector switches. For example, by virtue of this method of grouping in a ten thousand line exchange, the first selection or thousands selection is to select one of five groups of two thousand 95 each; the second selection or hundreds selection is to select one of four groups of five hundred in the selected group of two thousand; the third selection is to select one of five groups of one hundred out of 100 the selected group of five hundred; the fourth selection is to select one of ten groups of ten from the selected group of one hundred, and the fifth or final selection is to select a single line out of the selected group 105 of ten. Therefore, in a ten-thousand line system, in order to select a four-digit number, it is necessary to perform five selective

operations, or, in other words, to provide for five groups of controlling impulses, which impulses are provided for by the depression of a key for each digit, or, in the 5 case assumed, the depression of four keys.

In accordance with a related feature of the invention, a group of register relays is provided for each digit, and in addition relays are provided which, although they 10 perform their controlling operation independent of groups of relays, are adapted to be set in combination with such groups of relays. In accordance with this related feature of the invention, although a set of 15 keys, or other manually operated device, is provided for each digit of the required number, the register relays may be less in number than the number of keys, the operation of such keys being arranged to cause the 20 operation of more than one relay.

In accordance with another feature of the invention, in order that the register relays may perform their registering or storing functions, a locking circuit is provided for the 25 purpose of maintaining the relays energized in response to the depression of the keys after the keys have been released.

In accordance with another and related feature of the invention, the locking circuit 30 extends by way of a contact of all of the relays energized in any given group, so that it is not completed until the last relay of the group is energized. By virtue of this arrangement it is possible for the operator 35 to alter the designation of a number set up on the keys at any time before the last key is operated. The keys employed are of the type in which a depressed key is released by the depression of another key in the same 40 row, so that after the operator has discovered her mistake, by depressing the correct key she releases the previously depressed key, and as the locking circuit for the relays controlled by the keys has not been 45 established, the relay energized by the depression of the wrong key is released and is without effect.

In accordance with another feature of the invention, means are provided for releasing the depressed keys after the registering relays have performed their registering operation, and to simultaneously associate the registering relays with the apparatus to be controlled thereby in the controlling function of such relays, without delaying the controlling operation until after 55 the keys have been released.

In accordance with a related feature of the invention, however, means are provided 60 in case any depressed key fails to release at the proper time, thus creating an abnormal condition, whereby the controlling operation will be stopped and a signal displayed until such abnormal condition is removed 65 by an attendant.

Other features of the invention not specifically mentioned above will more clearly appear in the detailed description and the claims. In the accompanying drawings, Figures 1 and 2 show diagrammatically the 70 circuits of an incoming selector and a connector switch; Fig. 3 shows diagrammatically a cord finder for associating the registering and controlling device shown diagrammatically in Figs. 4, 5 and 6 with the 75 selector switch shown in Fig. 1. Fig. 7 shows, partly in section, details of the key-locking mechanism. The complete system is disclosed with Fig. 2 placed to the right of Fig. 1; Fig. 3 below Fig. 1; Fig. 4 below Fig. 3; Fig. 5 to the right of Fig. 4; and Fig. 6 below Fig. 4.

In the particular system in connection with which the invention is herein disclosed, the connecting circuit shown in Fig. 1 terminates in a selector switch, and is extended by an inter-office trunk to a manual operator's position. In such system the manual operator answers a call by inserting her answering plug in the jack of the calling line, 80 and after ascertaining the number communicates over a suitable order wire with an operator at a distant semi-automatic exchange, who assigns a trunk leading to a selector switch, such as shown in Fig. 1, 85 whereupon the operator at the manual exchange inserts the calling plug of her cord circuit into a jack leading to the other exchange. The selector and connector switches disclosed are of the panel type and are of 90 the construction disclosed in U. S. Patent No. 1,123,696, dated Jan. 5, 1915. The cord finder shown in Fig. 3 is also of the panel type and performs the same function as the cord finder disclosed in applicant's prior 95 Patent No. 1,168,319, patented January 18, 1916. The registering and controlling device consists of a set of keys, such as shown in Fig. 5, a plurality of register relays, such as shown in Fig. 4, and a set of counting 100 relays, as shown in Fig. 6. There are also provided in connection with various parts of the system, switches of the type known in the art as sequence switches, the construction of which is well known. The various 105 contacts operated by each of such sequence switches are grouped adjacent to the sequence switch, except in the case of the sender sequence switch shown in Fig. 3, certain of the contacts individual to such 110 sequence switch being shown on Fig. 4. In order to identify the sequence switch contacts with the particular sequence switch by which they are operated, the hundreds digit of the reference characters applied to all 115 sequence switch contacts is the same as the hundreds digit applied to the sequence switch. Thus sequence switch contact 321, for example, is individual to the sequence 120 switch 300.

It is thought that the invention may be best understood from a description of the operation of the system in establishing a typical call, for example, No. 9682.

5 It will be assumed that the allotter shown at the right in Fig. 3 has operated in the usual manner and has allotted the cord finder, also shown in Fig. 3, for use with the next incoming call. It will be further 10 assumed that the A operator at a distant office has received a call, has communicated with the B operator, that the two operators have communicated over a suitable order wire with the result that the B operator has 15 assigned an inter-office trunk for the particular call, and that the A operator has inserted plug of her jack, indicated at 1, into jack 2 of the inter-office trunk.

As soon as the B operator has assigned the 20 trunk she operates the assignment key indicated at 101; the operation of this key closes a circuit for sequence switch 100, which may be traced from battery through the motor magnet of the sequence switch 100, contact 25 102 (position 1), key 101 to ground. The sequence switch 100 thereupon moves into position 2. When the sequence switch 100 reaches position 2, circuit is established at contact 103 for relay 301 which circuit may 30 be traced as follows: from battery, relay 301, contact 306 (position 1), contact 103 (position 2), left-hand armature and back contact of relay 104 to ground. Relay 301 closes at its right-hand armature and front 35 contact a circuit for the sequence switch 300: from battery, motor magnet of sequence switch 300, contact 307 (position 1), front contact and armature of relay 301 to ground. Sequence switch 300 thereupon moves into 40 position 2, and in position 2 a circuit is established for the updrive magnet 302 of the cord finder indicated generally at 308, which circuit may be traced from battery, updrive magnet 302, contact 309 (position 45 2), front contact and armature of relay 301 to ground. In response to the energization of the updrive magnet 302, the brushes 310, 311 and 312 are moved over contacts 313, 314, 315 to which are connected conductors 50 leading to the connecting circuit, shown in Fig. 1. As soon as the sequence switch 300 passes position 1½ the original energizing circuit for the relay 301 is broken at the contact 306 and thereafter the relay 301 is 55 maintained energized by way of the contact 306 (positions 1½ to 17) to the back contact and left-hand armature of relay 303 to ground, or while the brushes of the cord finder are passing between terminals, by way 60 of the left-hand armature and front contact of relay 301, commutator segments 316, brush 337 to ground. Therefore, while brushes of the cord finder are passing over terminals which are individual to connecting circuits which have not been taken for 65

use, the relay 301 will be maintained energized and updrive magnet 302 will also remain energized. As soon as the brush 311, however, makes contact with the terminal 314, individual to the connecting circuit 70 shown in Fig. 1, a circuit is established for magnet 303 which may be traced as follows: from battery, relay 303, contact 317 (position 2), brush 311, terminal 314, contact 105 (position 2), back contact and right-hand 75 armature of relay 106, contact 107 (position 2), to ground. The relay 303 when energized opens at its left-hand armature one of the energizing circuits for the relay 301, which relay will, however, remain energized 80 over its alternative circuit until the brushes are accurately centered upon the terminals selected when such alternative circuit will be opened by the brush 337 making contact with an insulated segment of the commutator 85 316. When the relay 301 is thus deenergized the updriving magnet 302 is deenergized and the cord finder stopped by the brushes thereon in contact with the stationary terminals indicated at 313, 314 and 315. 90 The relay 301 when released also establishes a circuit for the sequence switch 300, which may be traced from battery, motor magnet of sequence switch 300, contact 307 (position 2), back contact and right-hand armature 95 of relay 301 to ground, whereupon sequence switch 300 moves into position 3, in which position such sequence switch will wait until the operator has set up the desired number on the sender shown in Figs. 4 100 and 5.

While the sequence switch 100, individual to the connecting circuit, is in position 2, a circuit is established for the lamp 108 which may be traced from battery through 105 the lamp 108, contact 109, in position 2, to ground. This lamp remains illuminated until the fundamental circuit is extended from the operator's sending device to the selector switch associated with the connecting 110 circuit.

Also, as soon as the relay 303 is operated, a circuit is established for relay 104 which may be traced from battery, relay 303, contact 317 (position 2), right armature and 115 front contact of relay 303, brush 310, terminal 313, conductor 110, contact 111 (position 2), relay 104, contact 112 (position 2), to ground. When the relay 104 is operated it connects ground to its previously traced energizing circuit at its left-hand armature and front contact, as a substitute for the ground at contact 112 in position 2. This relay is subsequently utilized in controlling the disconnection, and as such disconnection 120 forms no part of the present invention this subsequent operation of relay 104 need not be considered.

While the cord finder is hunting for the cord, the operator may be employed in set- 130

ting up the number upon her key set, shown at Fig. 5. It will be assumed that the number required is number 9682, so that the operator depresses the No. 9 key in the thousands row, the No. 6 key in the hundreds, the No. 8 key in the tens and the No. 2 key in the units row. These keys are latched in their depressed positions by latches controlled by the magnets indicated at 496. 5

10 As a result of the depression of these keys the following circuits are established: from battery to contact 318 (position 2), contact 4 of the allotter (position 1), relay 5, contact 6 of the allotter (position 1), conductor 7, contact 362 (position 3), contact 319 of the sequence switch 300 (position 3), conductor 433, left-hand winding of relay 400, conductor 434 to the upper contact of No. 9 key in the thousands row, and to ground at 15 435; from battery, contact 318 (position 3), contact 4, relay 5, contact 6, conductor 7, contact 362 (position 3), contact 319, (position 3), conductor 436, left-hand winding of relay 432, conductor 437, the lower contact of 20 the No. 9 key in the thousands row, to ground at 435; from battery, contact 318 (position 3), contact 4, relay 5, conductor 7, contact 362 (position 3), contact 320 (position 3), conductor 439, left-hand winding 25 of relay 408, conductor 440, upper contact of the No. 6 key in the hundreds row to ground at 435; from battery to contact 318 (position 3), contact 4, relay 5, contact 6, conductor 7, contact 319 (position 3), conductor 441, 30 right-hand winding of relay 430, conductor 442, lower contact of No. 6 key in the hundreds row to ground at 435; from battery, contact 318 (position 3), contact 4, relay 5, contact 6, conductor 7, contact 362 (position 3), contact 321, conductor 443, left-hand winding 35 of the relay 411, conductor 444, No. 8 key in the tens row, to ground at 435; from battery to contact 318 (position 3), contact 4, relay 5, contact 6, conductor 7, 40 contact 362 (position 3), contact 322 (position 3), conductor 445, left-hand winding of relay 427, conductor 446, No. 2 key of the units row, to ground at 435. The relays 400, 432, 408, 430, 411 and 427 of the register 45 and the relay 5 of the allotter are energized in these circuits. Relay 5 closes at its right-hand armature and contact a substitute circuit for the energized register relays independent of the battery at contact 318 in positions 1 to 3. This circuit extends from battery, right-hand armature and contact of relay 5, allotter contact 4 (position 1), relay 5, allotter contact 6 (position 1), and thence to ground at the depressed keys by way of 50 the energized register relays as previously traced. Therefore, in case all the keys are not released when the sequence switch 300 reaches position 4, the relay 5 is maintained energized and the circuit which drives the 55 sequence switch 300 out of position 4 is held 60 open at the back contact and left armature of the relay 5. Relay 430 energized in the circuits above traced closes a circuit from battery, left-hand armature and front contact thereof, relay 431 to ground, thus energizing relay 431. When the register relays are energized in the circuits above traced, two locking circuits for such energized relays are established; which locking circuits include the relays 304 and 305. The first of these locking circuits, which is established as soon as tens and units register relays have been operated, extends from battery indicated at 447, by way of the conductor 448, through the right-hand winding 65 of the relay 411, contact and right armature of such relay, conductor 449, conductor 450, conductor 451, right-hand winding of relay 427, contact and right armature of such relay, conductor 452, relay 304, contact 323 (position 3), to ground. Relays 427 and 411 are locked over this circuit. With the relay 304 energized and with the thousands and hundreds relays also operated, that is, with the relays 400, 432, 408 and 430 energized, 70 the following circuit is established: from battery (Fig. 4) to the left-hand winding of the relay 430, conductor 453, right-hand winding of the relay 400, contact and right-hand armature thereof, to conductor 454, 75 through the right-hand winding of relay 432, conductor 455, right-hand winding of the relay 408, contact and right-hand armature thereof, conductor 456, relay 305, armature and contact of 304, to ground. As the result of the establishment of these circuits just traced, relays 400, 432, 408, 430, 411 and 427 are locked, and the relays 304 and 305 are both energized. With relay 305 energized a circuit is established for the sequence switch 300 which may be traced from the battery to the motor magnet of sequence switch 300, armature and contact of relay 305, contact 323 (position 3) to the ground. 80 With the sequence switch 300 in position 100 4, a circuit is established for the release magnets 496, which when operated cause the release of all the depressed keys, this release circuit may be traced from battery, contact 318 (position 4), conductor 477, release magnets 496 in parallel to ground. Also in position 4 of the sequence switch 300, a circuit is established for the motor magnet 8 of the allotter, which may be traced from battery to the motor magnet 8 of the allotter, contact 329 in position 4, conductor 330, allotter contact 9 in position 1 to ground. The allotter thereupon moves into position 2. In position 2 of the allotter, assuming that the keys have been restored, the relay 5 is de-energized and a circuit is established to drive the sequence switch 300 into position 5, which circuit may be traced from battery, through the motor magnet of the sequence switch 300, contact 331 in position 4, left 105 110 115 120 125 130

5 armature and back contact of relay 5, allot-
6 ter contact 9 in position 2, to ground. Also
7 in positions 4 and 5 of the sequence switch
8 300, and in position 2 of the sequence switch
9 100, the so-called fundamental circuit lead-
10 ing to the first selector switch is established.
11 This circuit may be traced from bat-
12 tery (Fig. 1) to the winding of line relay 113
13 of the first selector switch, contact 114 (posi-
14 tion 2), conductor 115, terminal 315, brush
15 312, contact 324 (positions 4 and 5), step-
16 ping relay 325, conductor 457 to the back
17 contact and armature of the 0' counting re-
18 lay to ground.

19 Before describing the details of the se-
20 lecting operation which is now ready to
21 take place, it may be well to consider just
22 what selective acts are imposed upon the
23 system by the grouping of the lines therein,
24 in order to select the desired number,
25 namely, 9682. As the lines are divided into
26 five groups of 2,000 each, in order to reach
27 the group containing 9682 it will be neces-
28 sary to select the fifth or last group. There-
29 fore, the controlling impulses for the first
30 selection will be five in number. Having
31 selected the required group of 2,000, the
32 next selection will be one of four groups of
33 500 in such two thousand which, in the case
34 of the particular number under considera-
35 tion, will be in the group from 9,500 to 9,999.
36 This will be the fourth group of the group
37 from 8,000 to 9,999, and four controlling
38 impulses will be required. As the required
39 number will fall in the hundreds group ex-
40 tending from 9,600 to 9,699, which is a sec-
41 ond group of the thousands group 9,600 to
42 9,999, two controlling impulses will be re-
43 quired, and to select the eighth tens group
44 and second units group nine and three con-
45 trolling impulses respectively will be re-
46 quired. Thus it will be seen that five sets of
47 impulses are required to select the desired
48 number, being five, four, two, nine and
49 three. These impulses are all provided by
50 the depression of four keys, that is, No. 9 in
51 the thousands row, No. 6 key in the hun-
52 dreds row, No. 8 key in the tens row and
53 No. 2 key in the units row.

54 The relay 113 energized in the funda-
55 mental circuit above traced, closed at its
56 right armature and front contact, circuit of
57 the sequence switch 100 which may be traced
58 from battery to the motor magnet of se-
59 quence switch 100, contact 116 (position 2)
60 front contact and armature of relay 113 to
61 ground, whereupon the sequence switch 100
62 is driven into position 3. With the sequence
63 switch 100 in position 3 and relay 113 still
64 energized a circuit is established for the up-
65 drive magnet 117 of the first selector switch.
This circuit may be traced from battery,
magnet 117, contact 118 (position 3), con-
ductor 142, front contact and armature of
relay 113 to ground. The elevator rod 119

of the first selector, which carries the
brushes indicated at 120, 121 and 122, and
also the commutator brushes indicated at
123, moves upward. As soon as the second
brush to the left of the set of brushes 123
engages the first segment of the commutator
segment 124, the stepping relay 325 in the
fundamental circuit is shunted by the fol-
10 lowing path: from battery, relay 113, con-
11 tact 114 (position 2), conductor 125, contact
126 (position 3), conductor 127, commutator
128 segment 124, interrupter brush 123, con-
13 ductor 128, contact 129 (position 3) to the
14 ground.

15 Returning now to the operation of the 80
stepping relay 325, when this relay was first
16 energized, when the fundamental circuit was
17 established, with register relay 400 locked
18 up, a circuit was established from battery
19 through the No. 4 counting relay, armature
20 and back contact of the No. 4' counting re-
21 lay, conductor 458, contact and left arma-
22 ture of relay 400, conductor 459, contact 326
23 (position 4), contact 327 (position 4), arma-
24 ture and contact of relay 325 to ground. As 85
25 soon as the No. 4 counting relay is energized
26 a circuit is established for the No. 4' relay,
27 which may be traced from battery (Fig.
28 4), No. 4 relay, No. 4' relay, armature and
29 contact of No. 4 relay, conductor 460, con-
30 tact 328 (position 4) to ground. When the
31 interrupter brush of the selector switch
32 passes over the first segment of commu-
33 tator 124 as above described, the relay 325
34 is shunted. Upon the second energization 90
35 of the relay 325, counting relay No. 4' being
36 energized, the original energizing circuit
37 for the counting relay No. 4 is transferred
38 by the front contact and armature of No.
39 4' relay and back contact and armature of 95
40 No. 3' relay to the No. 3 relay, which there-
41 upon becomes energized and, as in the case
42 of No. 4 and No. 4' relays, as soon as the
43 No. 3 relay is energized, an energizing cir-
44 cuit is established for the No. 3' relay. 100
45 Thus after every energization and deen-
46 ergization of the stepping relay 325 a pair
47 of counting relays is energized, and as No. 4
48 counting relay was first energized, after five
49 energizations and deenergizations of the re-
50 lay 325 due to five shuntings thereof at the
51 commutator 124, the last or the No. 0' count-
52 ing relay will be energized. This relay when
53 energized opens at its back contact the pre-
54 viously traced fundamental circuit. As soon
55 as the fundamental circuit is opened the re-
56 lays 325 and 113 included in such circuit are
57 deenergized. The relay 113 when deener-
58 gized also opens the previously traced cir-
59 cuit for the updrive magnet 117. The relay
60 113 when deenergized closes at its right-
61 hand armature and back contact a circuit
62 for the sequence switch 100 which may be
63 traced from battery, to the motor magnet of
64 sequence switch 100, contact 198 in position 115

3, back contact and right armature of relay 113 to ground, whereupon the sequence switch 100 moves into position 4. When the No. 0' relay attracted its armature and 5 opened the fundamental circuit, a circuit was also closed for the sequence switch 300 to drive it into position 7, which circuit may be traced from battery, through the motor magnet of the sequence switch 300, 10 contact 331 (position 5), conductor 461, front contact and armature of the No. 0' counting relay to ground. As soon as the sequence switch 100 is driven into position 4, due to the deenergization of the relay 113, 15 a circuit is established for the brush tripping magnet indicated at 130. This circuit may be traced from battery, through the brush tripping magnet 130, contact 129 in position 4 to ground. As the brush tripping magnet is thus energized immediately 20 after five impulses are sent back to the sender, the tripping magnet 130 operates to trip the fifth set of brushes, which is assumed to be the set indicated on the drawing at 25 120, 121 and 122. With the sequence switch 300 in position 7, and 100 in position 4, the fundamental circuit is again established, which fundamental circuit may be traced from battery, through relay 113, contact 114 30 in position 4, conductor 115, terminal 315, brush 312, contact 324 in position 7, stepping relay 325, conductor 457 to the back contact and armature of the No. 0' counting relay, which relay has been deenergized, 35 due to the opening of its circuit at the contact 328, when the sequence switch 300 left position 5. As before, the stepping relay 325 and the line relay 113 are energized in this fundamental circuit. Relay 113 when 40 energized closes at its right-hand armature and front contact a circuit to drive the sequence switch 100 from position 4 to position 5. This circuit may be traced from battery, through the motor magnet of sequence switch 100, contact 116 (position 4), front contact and right armature of relay 113, to ground. The relay 113 also re-establishes the circuit previously traced for the updrive magnet 117. In position 5 of 45 the sequence switch 100, a shunt circuit for the relay 325 is established as soon as the relay 113 is energized, from battery, through the relay 113, front contact and left armature of such relay, contact 114 (position 5), conductor 125, contact 126 (position 5), commutator segment 131, brush to ground. This shunt circuit is established and interrupted as the shaft 119 is moved upward by the left-hand brush of the set of inter- 50 rupter brushes 123 in passing over the commutator segments 131. Thus the stepping magnet 325 is energized and deenergized a number of times, determined by the number of the counting relay energized when 55 the fundamental circuit is first established.

In position 7 of the sequence switch 300, as soon as the relay 325 is energized, with the relays 431 and 432 energized, a circuit is established for the No. 3 counting relay, which circuit may be traced from battery 70 (Fig. 6) through the No. 3 counting relay, armature and back contact of the No. 3' counting relay, conductor 462, conductor 463, right-hand armature and front contact of relay 431, front contact and left-hand armature of relay 432, conductor 464, contact 326 (position 7), contact 327 (position 7), armature and contact of relay 325 to ground. With the No. 3 counting relay thus energized, after the relay 325 has been energized 80 and deenergized four times, the No. 0' counting relay will be energized and will open at its back contact the fundamental circuit. The opening of the fundamental circuit causes the deenergization of the relay 113 which relay opens at its front contact the circuit of the updrive magnet 117 and closes at its back contact a circuit to drive the sequence switch 100 into position 6, which circuit may be traced from battery, through the motor magnet of sequence switch 100 in position 5, contact 198 in position 5, back contact and armature of relay 113 to ground. The No. 0' counting relay also closes at its front contact a circuit to 90 drive the sequence switch 300 out of position 7 into position 9, which circuit may be traced from battery, through the motor magnet of the sequence switch 300, contact 331 (position 7), conductor 461, front contact and armature of the 0' counting relay to ground. When the sequence switch 300 leaves position 7, the energizing circuit for the counting relays, by way of the conductor 460, is opened, permitting such counting 95 relays to restore.

With the sequence switch 100 in position 6, a circuit is established for the test relay 106 which may be traced from battery through the right-hand winding of relay 106, contact 133 (position 6) to ground. Relay 106, when energized, establishes a circuit to drive the sequence switch 100 into position 7, which circuit extends from battery through the motor magnet of sequence switch 100, contact 116 (position 6) left-hand armature and front contact of relay 106, contact 107 (position 6) to ground. In position 7 of the sequence switch 100, with the relay 106 energized, a circuit is established for the updrive magnet 117 of the first selector switch, which starts such selector switch in its trunk-hunting operation. This circuit extends from battery through the updrive magnet 117, contact 118 (position 7), contact 116 (position 7), left-hand armature and front contact of relay 106, contact 107 (position 7) to ground. During the hunting operation, the test relay 106 is maintained energized as long as the test 110 115 120 125 130

brushes 121 of the first selector switch are passing over terminals of busy lines by either of the two following circuits, one of which is effective while the brushes 121 are 5 actually in contact with the terminals of busy lines, and the other of which is maintained at all times while the brushes are passing between trunk terminals. The first of these circuits extends from battery 10 through the left-hand winding of relay 106, contact 134 (position 7), right-hand armature and front contact of relay 106, conductor 135, test brush 121, test terminal 136, armature and back contact of relay 201, contact 202, (which contact, in case the trunk to which it is individual leads to a busy final selector switch, is closed), to ground. If the particular trunk is idle, the contact 202 will be opened. The second energizing 15 circuit of the relay 106 extends from battery through the right-hand winding of the relay 106, contact 133 (position 7), conductor 137, commutator segment 138, and thence by way of the third brush of the set of interrupter 20 brushes 123, contact 116 (position 7), front contact and left-hand armature of relay 106, contact 107 (position 7), to ground. The brushes therefore will be moved over the stationary contacts until a test contact is 25 encountered which is individual to a trunk leading to an idle final selector, when the first energizing circuit for the relay 106 will be found open at contact 202. As soon as the second energizing circuit for the test 30 relay 106 is opened at the commutator 108 when the brushes are centered on the terminals, relay 106 will release. The release of the relay 106 opens the previously traced energizing circuit for the updrive magnet 35 117, stopping the elevator shaft 119 with the brushes 121 and 122 in contact with the terminals indicated at 136, 139 and 140. The relay 106, when released, also closes at its left-hand armature and back contact a circuit 40 to drive the sequence switch 100 from position 7 to position 8. This circuit may be traced from battery through the motor magnet of sequence switch 100, contact 141 (position 7), back contact and armature of relay 45 106, contact 107 to ground.

With the sequence switch 100 in position 8, sequence switch 300 in position 9, and the sequence switch 200 in position 1, after the first selector has operated to select a trunk 50 leading to an idle final selector, the fundamental circuit is again established. This circuit may be traced from battery, through the relay 113, contact 114 (positions 2 to 13), conductor 115, terminal 315, brush 312, contact 324 (position 9), stepping relay 325, conductor 457, to the back contact and armature of the No. 0' counting relay. The relays 113 and 325 are energized in this circuit. As a result of the energization of relay 55 113, a circuit is established to drive the sequence switch 100 into position 9, which circuit extends from battery, through the motor magnet of sequence switch 100, contact 116 (position 8), front contact and right armature of relay 113 to ground. The relay 113 also closes at its right-hand armature, a circuit for the relay 203, which circuit extends from battery, through the contact 204 (position 1), right-hand winding of the relay 203, contact 205 (position 1), trunk 75 conductor 206, terminal 139, brush 120, contact 118 (position 9), conductor 142, front contact and right-hand armature of relay 113 to ground. As a result of the energization of relay 203, a circuit is established for the relay 201 from battery, through relay 201, contact 207 (position 1), front contact and left-hand armature of relay 202 to ground. The relay 201 when actuated closes a circuit to drive sequence switch 200 into 80 position 2, which circuit extends from battery, through motor magnet of sequence switch 200, contact 208 (position 1), front contact and left armature of relay 201 to ground. This relay 201 is locked up by a circuit which extends from battery, through the relay 201, front contact and right armature thereof, terminal 136, brush 121, contact 107 (position 9) to ground. With the sequence switch 200 in position 2, a circuit is 85 established for the high speed updrive magnet 209 of the final selector, which circuit extends from battery, through the magnet 209, contact 210 (position 2), front contact and right armature of the relay 203, contact 100 205 (position 2), conductor 206, terminal 139, brush 120, contact 118 (position 9), conductor 142, front contact and armature of relay 113 to ground. Relay 113, after the sequence switch 100 reaches position 9, is 105 maintained energized during the movement of the elevator rod 211 of the final selector switch, while the second brush of the set of commutator brushes indicated at 212 passes over the commutator segment 213. The 110 energizing circuit for the relay 113 may be traced from battery, through the relay 113, left armature and front contact thereof, contact 114 (position 9), conductor 143, brush 122, terminal 140, conductor 213, contact 115 214 (position 2), contact 215 (position 2), to the commutator 213 and second brush in the set of interrupter brushes 212 to ground. This holding circuit for the relay 113 when 120 established by the commutator brush moving over the commutator segments 213 intermittently shunts the stepping relay 325. Thus, the movement of the final selector switch at this time is controlled by the operation of the counting relays, which counting 125 relays are in turn controlled by the operation of the stepping relay.

The register relay 408 having been energized, the No. 1 counting relay is energized at this time over a circuit which extends 130

from battery (Fig. 6), through the No. 1 counting relay, back contact and armature of the No. 1' counting relay, conductor 465, front contact and left-hand armature of the register relay 408 to conductor 466, contact 326 (position 9), contact 327 in position 9, and armature and front contact of relay 325 to ground. After the interrupter brushes 114 have passed over two segments of the commutator 113, and consequently after two shuntings of the relay 325, the No. 0' counting relay is energized, and opens the fundamental circuit, causing the deenergization of the relays 113, 325. The energization of the No. 0' counting relay also closes a circuit to drive the sequence switch 300 from position 9 to position 11, which circuit may be traced from battery, through the motor magnet of sequence switch 300, contact 381 (position 9), conductor 461 to the front contact and armature of the No. 0' counting relay to ground. As the sequence switch 300 leaves position 9, the original energizing circuit for the counting relays is opened and such counting relays restored to normal. When the relay 113 releases, a circuit is established to drive the sequence switch 100 from position 9 to position 10. This circuit extends from battery, through the motor magnet of sequence switch 100, contact 198 (position 9), back contact and right-hand armature of the relay 113 to ground. The release of the relay 113 also opens the circuit previously traced for the high speed updrive magnet 209 of the final selector switch, and also the circuit previously traced for the relay 203. Relay 203 when released closes at its back contact and left armature a circuit to drive the sequence switch 200 into position 3. This circuit may be traced from battery, through the motor magnet of sequence switch 200, contact 207 (position 2), back contact and left armature of the relay 203 to ground. When the sequence switch 200 reaches position 3, a circuit is established for the brush tripping magnet 216, which extends from battery, through the tripping magnet 216, contact 217 (position 3), to ground. The tripping magnet when operated at this time is arranged so that when the elevator 211 again moves upward, the second set of brushes carried by the elevator 211 will be tripped and rendered active. It will be assumed that such set of brushes are those indicated at 218, 219 and 220.

With the sequence switch 300 in position 11, the sequence switch 100 in position 10, and the sequence switch 200 (position 3), and the counting relays released, the fundamental circuit is again established for the purpose of controlling the tens selection, which fundamental circuit may be traced from battery, through the relay 113, contact 114 (position 10), conductor 115, terminal

315, brush 312, contact 324 (position 11), stepping relay 325, conductor 457, back contact and armature of the No. 0' counting relay to ground. The relays 325 and 113 are energized in this circuit. As a result of the energization of the relay 113, a circuit is established to drive the sequence switch 100 into position 11, which circuit extends from battery, through the motor magnet of the sequence switch 100, contact 116 (position 10), front contact and right armature of relay 113 to ground. As soon as the sequence switch 100 reaches position 11, the following circuit is established from battery, contact 204 (position 3), right-hand winding of relay 203, contact 205 (position 3), trunk conductor 206, terminal 139, brush 120, contact 118 (position 11), conductor 142, front contact and right armature of relay 113 to ground. The energization of the relay 203 closes a circuit to drive the sequence switch 200 into position 4, which circuit extends from battery, through the motor magnet of sequence switch 200, contact 207 (position 3) left armature and front contact of 203 to ground. With the sequence switch 200 in position 4, a circuit is established for the high speed updrive magnet 209 of the final selector, which circuit extends from battery, through motor magnet 209, contact 210 (position 4), right armature and front contact of relay 203, conductor 205 (position 4), trunk conductor 206, terminal 139, brush 120, contact 118 (position 11), conductor 142, front contact and right armature of the relay 113 to ground. A shunt circuit in derivation of the fundamental circuit is also established at this time, which circuit extends from battery, through the relay 113, contact and left armature thereof, contact 114 (position 11), conductor 143, brush 122, terminal 140, conductor 218, contact 214 (position 4), contact 215 (position 4), to commutator segment 221, and by way of the first set of the set of interrupter brushes 212 to ground. Therefore, as the elevator rod 211 is driven upward, the interrupter brushes passing over the commutator 221 will intermittently shunt the stepping relay 325 a number of times, depending upon the particular counting relay which has been energized. Returning now to the first energization of the relay 325, when the fundamental circuit was again established with the register relay 411 energized, a circuit is established for the No. 8 counting relay which may be traced from battery, through the No. 8 counting relay, back contact and armature of the No. 8' counting relay, conductor 467, front contact and left armature of relay 411, through conductor 468, contact 327 (position 11), armature and front contact of relay 325 to ground. Therefore, after nine shuntings of the relay 325, the fundamental circuit previously traced will be opened by the energi-

zation of the No. 0' counting relay. The opening of the fundamental circuit causes the deenergization of the relays 113 and 325. The energization of the relay 0' at this time establishes a circuit to drive the sequence switch 300 into position 13, which circuit may be traced from battery, through the motor magnet of the sequence switch 300, contact 331 (position 11), conductor 10 461, front contact and armature of the No. 0' counting relay to ground. The deenergization of the relay 113 opens the previously traced circuits for the updrive magnet 209 and for the relay 203. The relay 113 15 when released also closes a circuit to drive the sequence switch 100 into position 12, which circuit may be traced from battery, through the motor magnet of sequence switch 100, contact 198 (position 11), back 20 contact and right armature of the relay 113 to ground. The deenergization of the relay 203 establishes a circuit to drive the sequence switch 200 into position 5, which circuit extends from battery, through the 25 motor magnet of sequence switch 200, contact 207 (position 4), back contact and left-hand armature of the relay 203 to ground.

With the sequence switch 300 in position 13, the sequence switch 100 in position 12, and the sequence switch 200 in position 5, a fundamental circuit is again established to control the units selection. This fundamental circuit may be traced from battery, through the relay 113, contact 114 (position 30 12), conductor 115, terminal 315, brush 312, contact 324 (position 13), stepping relay 325, conductor 457, back contact and armature of the No. 0' counting relay to ground. Relays 113 and 325 are energized in this 35 circuit as usual. The energization of the relay 113 at this time establishes a circuit to drive the sequence switch 100 from position 12 into position 13, which circuit extends from battery, through the motor magnet of 40 the sequence switch 100, contact 116 in position 12, front contact and right-hand armature of the relay 113 to ground. With the sequence switch 100 in position 13, and the sequence switch 200 in position 5, a circuit is 45 established for the relay 203, which extends from battery, through the contact 204 (position 5), right-hand winding of the relay 203, contact 205 (position 5), conductor 206, terminal 139, brush 120, contact 118 (position 55 13), front contact and right-hand armature of the relay 113 to ground. The relay 203 when energized establishes a circuit to drive the sequence switch 200 from position 5 to position 6, which circuit extends from 60 battery, through the motor magnet of the sequence switch 200, contact 207 (position 5), front contact and left armature of the relay 203 to ground. With the sequence switch 200 in position 5, a circuit is established from a slow-speed updrive magnet 65 222, which circuit may be traced from battery, through the magnet 222, contact 210 (position 6), front contact and right-hand armature of relay 203, contact 205 (position 6), trunk conductor 206, terminal 139, brush 70 120, contact 118 in position 13, conductor 142, front contact and armature of the relay 113 to ground. With the relay 113 energized, a shunt circuit in derivation of the fundamental circuit is established including 75 the commutator 223 of the final selector switch, which circuit extends from battery, through the relay 113, front contact and left armature thereof, contact 114 (position 13), conductor 143, brush 122, terminal 140, conductor 213, contact 214 (in position 6), contact 215 (position 6), commutator 213 to ground, through the middle brush of the set of interrupter brushes indicated at 212. In the meanwhile, when relay 325 is energized, 80 and with the register relay 427 energized, a circuit is established for the No. 2 counting relay, which circuit extends from battery, through the No. 2 counting relay, armature and back contact of the No. 2 counting 85 relay, conductor 469, front contact and right-hand armature of the relay 427, conductor 470, contact 327 (position 13), armature and front contact of the relay 325 to ground. Therefore, after three shuntings of the relay 325, the fundamental circuit is opened 90 by the energization of the No. 0' relay, causing the deenergization of the relays 113 and 325. The relay 0' closes at its front contact a circuit to drive the sequence switch 100 300 out of position 13 into position 16. This circuit extends from battery, through the motor magnet of sequence switch 300, contact 331 (position 13), conductor 461, armature and front contact of the No. 0' counting relay to ground. When the sequence switch 300 reaches position 16, such sequence switch waits until the sequence switch 100 leaves position 13, when the previously traced energizing circuit for the relay 303 105 is opened, and the sequence switch 300 is driven into position 17, over a circuit which extends from battery, through the motor magnet of sequence switch 300, contact 307 (position 16), back contact and armature of 110 relay 303 to ground. In position 17 of the sequence switch 300, a circuit is established for the downdrive magnet of the cord finder, which restores such cord finder to normal 115 position. This circuit extends from battery, through the downdrive magnet 332, contact 306 (position 17), back contact and armature of relay 303 to ground. When the cord finder has completely restored, the brush 337 makes contact with the contact 333, when a 120 circuit is established to drive the sequence switch 300 from position 17 to position 18. This circuit extends from battery, through the sequence switch 300, contact 334 (position 17), contact 333, and brush 317 to 130

ground. The sequence switch 300 remains in position 18 until the allotter allots the cord finder for use in another connection.

- With the cord finder restored to normal 5 position, the registering and controlling equipment is disconnected from the connecting circuit. In the meantime the opening of the fundamental circuit has caused the brushes of the final selector to stop in contact with the terminals of the desired line. It will be recollect that when the fundamental circuit was opened at the counting 10 relays, relay 113 was deenergized, opening at its front contact and right armature, previously traced circuit for the relay 203 and the updrive magnet 222. Relay 113 also closes at its back contact a circuit to drive the sequence switch 100 out of position 13 into position 14, which circuit extends from 15 battery to the motor magnet of the sequence switch 100, contact 198 (position 13), back contact and right armature of relay 113 to ground. The deenergization of the relay 203 establishes a circuit to drive sequence switch 20 200 from position 6 into position 7, which circuit extends from battery through the motor magnet of the sequence switch 200, contact 207 (position 6), back contact and left armature of relay 203 to ground. 25
- As the invention claimed in this application has to do with the operation of the registering and sending device and is not concerned with the operations of the system after such registering and sending device has 30 been disconnected from the connection being established, it is thought to be unnecessary to describe the testing operation and subsequent operations at the final selector switch or to describe such operations as supervision 35 and disconnect which take place independently of, and after the operation of the registering and sending device.

- A complete connection has been traced in detail in which all of the selecting operations necessary in extending the connection to a typical line have been described. It is, therefore, thought that no difficulty should be encountered in understanding just how connections to other lines may be extended. 45
- The only difference in the operation being that the register relays are operated in different combinations to provide the necessary impulse combination to select a particular line. In all cases, however, the extra set 50 of impulses will be controlled by means of the relays 430, 431 and 432.

- In addition to illustrating the feature of translation in the registering and controlling equipment, the normal connection traced 55 above will also serve to illustrate certain other features of the invention. For example, from the connection traced it may be observed that the locking circuit for the various registering relays extends by way of 60 an armature and contact of each of the re-

lays energized by the operation of any given combination of keys. Therefore, this locking circuit is not established until after the last relay has been energized.

It should also be noted that in the normal 70 operation of the system the fundamental circuit is established to control the first selective operation as soon as the equipment sequence switch 300 reaches position 4, in which position the keys are also released. 75 This fundamental circuit is also maintained in position 5 of the sequence switch 300, to which position the sequence switch moves as soon as the keys are released. It has heretofore been the practice to delay the first selective operation until after the keys have 80 been released, which delay involved the loss of a certain amount of time in establishing a connection.

Attention may be directed at this point 85 to the fact that the particular form of key which is adapted to be used with the registering and controlling equipment disclosed is of the type in which the depression of any key mechanically releases previously depressed keys in the same row. A key structure of this type is illustrated in Fig. 7, but as such structure is well-known, it is not deemed necessary to describe it in detail. As 90 keys of this type are employed and as the locking circuit of the relays which are energized in response to the operation of the keys is not closed until the last relay has been operated, hence until the last key has been depressed, it is possible for the operator to 95 change the designation represented by the keys operated. Therefore, if the operator should make a mistake in depressing the keys, this mistake may be rectified provided it is discovered before the last key is depressed. For example, if the operator had, in response to the request for line No. 9682, depressed No. 9 key in the thousands row, No. 7 key in the hundreds row and No. 7 key 100 in the tens row, and then discovered her mistake, this mistake could be rectified by pressing the No. 6 key in the hundreds row and the No. 8 key in the tens row, which act would mechanically release the keys depressed in error, and, as the locking circuits 105 had not been established for the corresponding registering relays, such registering relays would be deenergized.

It may also occur under abnormal conditions that a key will fail to release in response to the energization of the release magnets 456 when the sequence switch 300 reaches position 4, in which case, if the call were permitted to proceed, a subsequent connection might be mutilated. It is always 110 advisable in telephone exchange systems to remove an abnormal condition as soon as possible after such condition arises. Therefore, in accordance with the system disclosed, means are provided for holding up 115

the selection in case an abnormal condition, such as above described, should develop. It will be recalled that the relay 5 of the allotter is energized over a circuit which extends 5 in parallel through all of the depressed keys, and also that the sequence switch 300 cannot leave position 4 until the relay 5 is de- energized. Therefore, in case a key fails to 10 restore in response to the energization of the release magnets, the relay 5 remains energized, and the sequence switch 300 will remain in position 4. From positions 2 to 4 of the sequence switch 300 the lamp 363 is illuminated by a circuit which extends from 15 battery by way of contact 364 to ground. Consequently, if this lamp remains illuminated for an abnormal period, as would be the case when a key fails to restore, the operator will notify an attendant of the abnormal condition, and such attendant may then 20 locate the faulty key and remove such abnormal condition.

While the registering and controlling equipment, shown in Figs. 3, 4, 5 and 6, has 25 been described in connection with the particular system disclosed in Figs. 1 and 2, it will be obvious to any one skilled in the art that the registering and controlling equipment may be associated with systems widely 30 varying in character, without departing from the spirit of the invention.

What is claimed is:

1. A registering and controlling equipment for telephone exchange systems comprising a plurality of sets of register relays, a manually operable device for each digit of the greatest number it is desired to register, certain of such register relays being operated in response to the operation of such 35 manually operable devices to control the production of a set of impulses for each digit of the number registered, and means associated with such relays for controlling the production of an additional set of impulses.
4. A registering and controlling equipment for telephone exchange systems comprising a plurality of sets of register relays, a manually operable device for each digit of the greatest number it is desired to register, 40 such register relays being selectively operated in response to the operation of said manually operable devices and when so operated serving to control the production of a set of controlling impulses for each digit of such devices, and means controlled from such manually operable device for controlling the production of an additional set of impulses independent of such register relays.
5. A registering and controlling equipment for telephone exchange systems comprising a set of keys for each digit of the greatest number it is desired to register, a 45 register relay circuit associated with said keys and having a plurality of relays therein less in number than the number of keys and selectively operable in groups in response to the combinations of keys set by the operator, and locking means for the operated group of relays operating upon the energization of the last one of the selectively operable group of relays, whereby the group of relays is held in operated position irrespective of the subsequent condition of the keys.

6. A registering and controlling equipment for telephone exchange systems comprising keys adapted to be set by the operator in combinations to represent any line number of the system, a register relay circuit associated with said keys and having a plurality of relays therein arranged in groups, said relays being selectively operable in combinations corresponding to the 50 combinations of keys depressed by the operator, and locking means for the operated combination of relays operating upon the energization of the last one of the selected combination of relays whereby the combina- 55
7. A registering and controlling equipment for telephone exchange systems comprising keys adapted to be set by the operator in combinations to represent any line number of the system, a register relay circuit associated with said keys and having a plurality of relays therein arranged in groups, said relays being selectively operable in combinations corresponding to the 55 combinations of keys depressed by the operator, and locking means for the operated combination of relays operating upon the energization of the last one of the selected combination of relays whereby the combina- 60

adapted to be selectively operated in response to the operation of such keys and to control the production of a set of controlling impulses for each set of relays, and additional relays also controlled by the operation of such keys to produce an additional set of controlling impulses.

4. In a registering and controlling equipment for telephone exchange systems, a plurality of sets of keys, a corresponding plurality of sets of register relays, means controlled by the operation of any one of a plurality of keys in a set of keys to select a relay of the corresponding set of register relays, additional relays, means controlled 75 by the operation of the same one of the same set of keys to determine the operation of an additional relay, and means jointly controlled by the selected register relay and said additional relay to control selection in an 80 automatic switch in accordance with the number represented by the depressed keys.

5. In a registering and controlling equipment for telephone exchange systems, a set of keys for each digit of the number it is 90 desired to register, a corresponding set of register relays one of which may be selected by the operation of either one of a pair of keys, an additional relay the operation of which is determined by the particular key 95 operated in such pair, and means controlled by the selected register relay and the additional relay to control selection in an automatic switch in accordance with the number represented by the operated key.

6. A registering and controlling equipment for telephone exchange systems comprising keys adapted to be set by the operator in combinations to represent any line number of the system, a register relay circuit associated with said keys and having a plurality of relays therein less in number than the number of keys and selectively operable in groups in response to the combinations of keys set by the operator, and locking means for the operated group of relays operating upon the energization of the last one of the selectively operable group of relays, whereby the group of relays is held in operated position irrespective of the subsequent condition of the keys.

7. A registering and controlling equipment for telephone exchange systems comprising keys adapted to be set by the operator in combinations to represent any line number of the system, a register relay circuit associated with said keys and having a plurality of relays therein arranged in groups, said relays being selectively operable in combinations corresponding to the 120 combinations of keys depressed by the operator, and locking means for the operated combination of relays operating upon the energization of the last one of the selected combination of relays whereby the combina- 125

tion of relays is held in operated position irrespective of the subsequent condition of the keys.

8. A registering and controlling equipment for telephone exchange systems comprising keys adapted to be set by the operator in combinations to represent any line number of the system, and a register relay circuit associated therewith operating in response to and registering or storing up the designation of the line number set up by the operator, said register relay circuit comprising a plurality of relays arranged in groups and adapted to be operated in predetermined combinations, each relay having a locking winding associated therewith, locking circuits including said locking windings, said locking circuits being completed to maintain the energized relays in their operated position only after the energization of the last relay of the selected combination.

9. In a telephone exchange system, a controlling device comprising a plurality of sets of keys adapted to be depressed in varying combinations, means for locking the depressed keys, electromagnetic releasing means for unlocking said keys, a selection controlling circuit leading from said controlling device to the apparatus controlled thereby, and means responsive to the depression of the last key to establish immediately thereafter the selecting circuit and a circuit for such electromagnetic key releasing means.

10. In a telephone exchange system, a registering and controlling equipment including a plurality of keys adapted to be operated in various combinations to correspond with the number of any subscriber in the system, a register relay circuit having a plurality of relays therein operated in predetermined groups in response to the depression of a combination of keys by an operator for registering the number corresponding thereto, means for mechanically locking the operated keys in their depressed position, electrical means for releasing the depressed keys, a selecting circuit, and means for simultaneously operating the key releasing means and closing the selecting circuit.

11. In a telephone exchange system, registering and controlling equipment including a plurality of keys adapted to be operated in varying combinations to correspond with the number of any subscriber in the system, a register relay circuit having a plurality of relays therein operated in predetermined groups in response to the depression of a combination of keys by the operator for registering the number corresponding thereto, means for mechanically locking the operated keys in their depressed position, electrical means for releasing the

depressed keys, a selecting circuit, means for simultaneously operating the key-releasing means and closing the selecting circuit, and a counting relay circuit directly controlled by the selecting circuit.

12. In a telephone exchange system, a registering and controlling equipment including a plurality of keys adapted to be operated in varying combinations to correspond with the number of any subscriber in the system, a register relay circuit having a plurality of relays therein operated in predetermined groups in response to the depression of a combination of keys by the operator for registering the number corresponding thereto, means for mechanically locking the operated keys in their depressed position, electrical means for releasing the depressed keys, a selecting circuit, means for simultaneously operating the key-releasing means and closing the selecting circuit, and a counting relay circuit indirectly controlled by the register relay circuit and directly controlled by the selecting circuit.

13. In a semi-automatic telephone exchange system, the combination with a plurality of register relays, of a plurality of manually operated devices for selecting predetermined groups of said plurality of register relays, said selected group corresponding to the combination of manually operated devices, means for allowing the designation determined by the plurality of manually operated devices to be altered at any time previous to the operation of the final one of said manually operated devices.

14. In a semi-automatic telephone exchange system, a plurality of series of register relays, a plurality of rows of keys, said rows corresponding in number to the number of the series of register relays and operating, when a key of each row is depressed, to energize a predetermined group of register relays, one or more relays for each series of relays being energized to form the group of relays, the group of relays being completed only upon the energization of the last relay of the group, a locking circuit for said group of relays completed only when the last relay of the group is energized, whereby the line designation may be altered at any time previous to the closing of said circuit.

15. In a telephone exchange system, a controlling device comprising a plurality of sets of keys, means for locking operated keys in operated position, means for releasing said keys and restoring them to non-operated position, and means controlled by the operation of any key serving to stop the controlling operation of the controlling device until all the keys are restored to non-operated position.

16. In a telephone exchange system, a registering and controlling equipment, a plu-

5 rality of registering and controlling devices, a plurality of keys adapted to be operated to selectively control the registering operation of such registering and controlling devices, an automatic switch for associating such registering and controlling devices with the apparatus to be controlled thereby, means for restoring the operated keys, and means operated by the depression of any 10 key for stopping the operation of such automatic switch in case all the keys are not restored.

15 17. In a telephone exchange system, a registering and controlling equipment comprising a plurality of registering and controlling devices, a plurality of keys adapted when depressed to control the registering operation of such registering and controlling devices, an automatic switch for simultaneously releasing the depressed keys and 20 associating said registering and controlling devices with a portion of the apparatus to

be controlled, and means controlled by the depression of any key serving to prevent the further operation of such switch and registering and controlling devices in case a depressed key fails to restore. 25

18. In a telephone exchange system, a controlling device comprising a plurality of sets of keys, means for locking operated 30 keys in their operated position, means for releasing said keys, means for restoring such keys to non-operated position, means controlled by the operation of any key serving to stop the controlling operation of the controlling device until all keys are restored to non-operated position, and means for indicating an abnormal delay in the operation of such controlling device. 35

In witness whereof, I hereunto subscribe 40 my name this 27th day of October A. D., 1916.

ALBEN E. LUNDELL.
